Frank Warren

UNITED STATES PATENT OFFICE

FREDERICK A. BRUNS, OF BLAINE, WASHINGTON.

SEPARATOR.

1,327,903.

Specification of Letters Patent. Patented Jan. 13, 1920.

Application filed May 27, 1919. Serial No. 300,213.

To all whom it may concern:

Be it known that I, FREDERICK A. BRUNS, a citizen of the United States, residing at Blaine, in the county of Whatcom and State 5 of Washington, have invented a certain new and useful Improvement in Separators, of which the following is a specification.

My invention relates to improvements in separators for washing sand, gravel and the 10 like and the object of my invention is to provide a separator that is simple in its plan of construction and efficient in its operation.

A further object is to provide a separator 15 wherein the material that is being washed is permitted to drop by gravity through passageways through which water is caused to flow upwardly in such manner that the water will serve to thoroughly wash the 20 sand or gravel and to remove therefrom any particles of lighter material, as pine needles, chips of water soaked wood and the like.

Other and more specific objects will be apparent from the following description taken in connection with the appended claims.

I accomplish these objects by devices illustrated in the accompanying drawings, wherein—

30 Figure 1 is a view in vertical section substantially on broken line 1, 1 of Fig. 2 of a separator constructed in accordance with my invention;

Fig. 2 is a view in vertical cross-section 35 of the same substantially on broken line 2, 2 of Fig. 1;

Fig. 3 is a view in cross-section of a detail of my invention; and

Fig. 4 is a view in cross-section on broken 40 line 4, 4 of Fig. 3 certain parts of which being shown in plan.

Referring to the drawings throughout which like reference numerals indicate like parts, the numeral 5 designates a rectangular box having a top side comprising a fixedly mounted inclined portion 6, a rigidly mounted horizontal portion 7 and a swingingly mounted door 8.

Disposed between the door 8 and the horizontal portion 7 are suitable frame members 10 that form a receptacle for supporting a removable block 11.

The block 11 is provided with a plurality of transverse triangularly-shaped strips 12 55 that are removably secured to the top side of such block and are arranged in spaced apart

relation so that they form a plurality of transverse troughs 13.

Extending through the block 11 and terminating in the trough portions 13 are 6 perforations 14 of any desired size, depending upon the size of the sand or gravel that is to be washed.

Disposed upon the triangular strips 12 and arranged to be moved transversely of 6 the block 11 to agitate the sand or gravel that falls upon such block 11 is a grating or jigger 15 that is provided at each of its opposite ends with an upwardly projecting bar 16 that is connected by links 17 with eccentric pins 18 on disks 19 that are secured to opposite ends of a transverse shaft 20 so that when the shaft 20 is rotated by any suitable source of power, not shown, the jigger 15 will be reciprocated on the 75 block 11.

Spaced above the block 11 and adjustably mounted in grooves 21 in upright members 22 are a plurality of slats or distributing bars 23 that form an adjustable grating 80 whereon material and water may be delivered from a chute 24. The chute 24 is adjustable vertically and longitudinally by means of bolts 25 which pass through slotted holes 26 in the sides of the chute 24 and 85 through slotted holes 27 in the upwardly projecting portions 28 of the ends of the box 5.

The inclined wall portion 6 over which the water is discharged is provided with a 90 transverse bar 30 that is adjustably supported by brackets 31 having bolts 32 that pass through slots 33 in the ends 28 of the box 5, the block 30 being adapted to be moved up or down the inclined top portion 95 6 to regulate the depth of water on the top of the perforated block 11.

Disposed below the perforated block 11 and extending lengthwise thereof are a plurality of jetting devices indicated generally 100 by the numeral 34 each of which jetting devices comprises a relatively long triangularly-shaped receptacle that is provided in its top side or apex with perforations 35 and in its bottom with an arcuate wall 36 105 that divides the interior of the jetting devices into an upper compartment 37 and a lower compartment 38.

The lower compartment 38 of each of the jetting devices 34 is connected at a point 110 about one fourth of the distance from each end with a pipe 40 which in turn is con-

nected by a T-fitting 41 with a vertically arranged pipe 42 that is provided with a valve 43 and is connected with a larger horizontal pipe 44 that communicates by means 5 of a pipe 45 with a tank 46 wherein water may be stored.

The T-fittings 41 are each provided with removable plugs 47 which permit the pipes 40 and 42 to be drained. The arcuate wall 10 36 is provided with a plurality of perforations which permit matter to pass upwardly from the compartment 38 into the compartment 37, the perforations at the points directly above the inlets of the pipes 40 being 15 relatively small as indicated at 48 and such perforations being of gradually increasing size at points removed from the inlets of the pipes 40 so that water from the chamber 38 may be evenly distributed throughout the 20 length of the chamber 37 and will issue with equal force from all of the perforations 35.

The jetting devices 34 are positioned so that the perforations 35 are directly below the perforations 14 in the block 11 whereby 25 water that is emitted from the perforations 35 will be jetted upwardly through the perforations 14 in the block 11 at the same time that sand or gravel is passed downwardly through such perforations thereby serving 30 to thoroughly wash the sand or gravel and to prevent any particles of lighter material from passing downwardly into the box 5.

By maintaining a substantially constant height of water in the tank 46 it is possible 35 to maintain a substantially constant pressure within the chambers 37 of the jetting devices, the water from the tank 46 being distributed by the relatively large pipes 44 with substantially equal pressure to all of 40 the pipes 42 and such water being distributed by means of the perforations of graduated size in the arcuate wall 36 at substantially constant pressure to the chamber 37.

45 Disposed above the block 11 and adjacent the rear edge thereof is a perforated water pipe 50 that may be used for spraying water upon the top of the perforated block 11 if desired.

50 The distributing bars 23 are adjustable so that the spaces therebetween may be varied to grade and evenly distribute the materials that fall on the block 11. In practice the bars 23 will ordinarily be closer together at 55 the point where the material comes on to such bars and will be spaced at gradually increasing distance toward the discharge end thereof so that the larger material will be carried over to a point near the discharge 60 edge of the block 11 before it is dropped on such block.

Sand or gravel and water may be delivered by a spout 51 into the chute 24 and may be discharged therefrom on to the distributing bars 23.

As the sand and water passes over the chute 24 the sand or gravel will tend to settle in the bottom of such chute while the water will tend to flow on top thereof, and, for the purpose of removing the surplus water, 70 if more water than is needed for washing the material, is passing over the chute 24, I have provided a relatively shallow pan or chute 52 having its upper end adjustably secured by means of a bolt 53 and slot 54 to the end of the chute 24 and its lower end adjustably secured by means of a bolt 55 and slotted link 56 to the upper portions 28 of the end walls of the box 5.

The box 5 is provided in its opposite ends 80 with transparent plates or windows 57 through which the accumulation of sand therein may be observed and which further enables the observer to determine whether or not the water in the box is clear or muddy 85 to thereby determine whether or not the sand is being thoroughly washed.

The box 5 is provided at one or more points with openings 58 that are adapted to be closed by slides 59 and through which 90 washed sand or gravel may be removed.

In the operation of my device the sand or gravel together with a considerable amount of water is delivered from the trough 51 into the chute 24 thence passes downwardly on to the distributing bars 23, the excess water being taken off over the pan 52, the sand will drip downwardly between the bars 23 on to the top of the block 11 where it will be agitated and kept moving by the upward current of water emitted through the perforations 14 and by the reciprocating movement of the jigger 15.

All of the particles of sand and gravel will eventually pass downwardly through 105 the perforations 14 while the lighter materials as floating chips, pine needles, clay, dirt and the like will be washed away by the upward flow of water through the perforations 13 and will pass over the inclined top 110 portion 6 of the box 5.

In practice the sand or gravel will preferably be screened before it is delivered into the chute 24 so that no pieces that are too large to pass through the perforations 14 115 will be delivered on to the block 11.

In instances where a constant stream of sand or gravel is delivered from the chute 51 it may be advantageous to employ two or more of my separators so that the flow of 120 sand or gravel may be directed into one separator while the washed material is being removed from the other.

It will be obvious that changes in the precise form of construction of the various 125 parts of my invention may be resorted to within the scope of the following claims.

What I claim is:

1. A separator of the class described comprising a perforated block having trough 130

- like channels on the top side thereof; an agitator reciprocable on the top of said block; means for delivering material on to said block; and means for directing a jet of water upwardly through each of the perforations in said block.
2. A separator of the class described comprising a receptacle; a perforated block supported in the top side of said receptacle; an agitator reciprocable on the top side of said block; a grating arranged above said block to distribute material evenly over said block; a chute for delivering water and material to be washed on to said grating; and means arranged below said block for delivering a jet of water upwardly through each of the perforations in said block.
3. A separator of the class described comprising a receptacle; a perforated block supported in the top side of said receptacle; adjustable distributing bars arranged above said block; a chute for delivering water and material to be washed on to said distributing bars; means for regulating the depth of water on said block; and means arranged below said block for delivering a jet of water upwardly through each of the perforations in said block.
4. A separator of the class described comprising a block having removable triangularly-shaped strips extending crosswise thereof, the said strips being spaced apart to leave trough-like depressions therebetween; perforations extending through said block and terminating in said trough-like depressions; an agitator reciprocable on the top of said strips; distributing bars adjustably disposed above said block; means for delivering water and material to be washed on to said distributing bars; and means for directing jets of water upwardly through the perforations in said block.
5. A separator of the class described comprising a perforated block, means for delivering material to be washed on to said block; a plurality of jetting devices arranged below said block, each of said jetting devices comprising a relatively long receptacle of triangular cross-section having perforations in the apex thereof that are arranged directly below the perforations in said block and each of said jetting devices having an upper water chamber and a lower water chamber that communicate through a perforated wall with said upper water chamber whereby the pressure in said upper water chamber will be substantially equal for all points within the chamber; a water supply tank; and valve-controlled conduit means connecting said water supply tank with the lower chamber in each of said jetting devices.

In witness whereof, I hereunto subscribe my name this 21st day of May, A. D. 1919.

FREDERICK A. BRUNS.
